UNITED STATES PATENT OFFICE.

RAYMOND HUFFORD, OF NEW YORK, AND HERMAN G. ADLER, OF BROOKLYN, NEW YORK, ASSIGNORS TO K. P. PRODUCTS CO. INC., OF NEW YORK, N. Y., A CORPORATION OF NEW YORK.

GOVERNOR FOR INTERNAL-COMBUSTION ENGINES.

Application filed September 1, 1926. Serial No. 133,040.

This invention relates to internal combustion engine governors adapted to maintain a substantially constant engine speed under varying load conditions.

To that end the invention contemplates a governor that will not restrict the power development of the engine and which will be sensitive to small variations in speed and load. Heretofore, in other vacuum governors, the variations of the vacuum have been balanced by the use of linkage mechanism, or cams which are unsatisfactory because of the excessive friction produced with consequent wear.

Accordingly, the invention has in view a novel construction and arrangement of parts involving a directly connected governing valve and vacuum responsive element and spring resistance which will obviate the difficulties set forth and in which the differential between the pressure in the intake duct and atmospheric pressure acting upon the piston tends to close the valve. In that connection the invention also contemplates a governing valve adapted to so move across the intake duct that the impact of the mixture will not tend to influence the movement of said valve. The invention also contemplates a guide stem on the governing valve extending across the intake duct and into a guide on the opposite side of the duct which prevents the valve from cocking when subjected to the vacuum on the engine side of the duct and the impact of the mixture thereon and thereby greatly reduces the friction attendant upon the movement of the valve toward or from its closed position.

Another object of the invention is to so regulate the vacuum acting upon the vacuum responsive member so as to compensate for any inaccuracy in the springs which oppose the movement of the vacuum responsive member, the varying vacuum characteristics of different motors and varient air leaks past the vacuum responsive member.

A further object of the invention is to provide a constantly increasing spring resistance to the closing movement of the governing valve which is increased by equal increments to accurately balance the vacuum effort of the vacuum responsive element under all load and main throttle settings. This spring resistance may assume various

forms according to the design of the governor and its particular application to motors of different types. In that connection the resistance element includes spring means having sections thereof of such varient coiled pitch that they progressively go out of action during the movement of the valve. A still further object of the invention is to provide a simple, practical and reliable construction which is easy to manufacture and assemble and when installed for use requires a minimum of service and attention, and incorporates means for locking the same in the desired position, thereby rendering the device tamper-proof.

With the above and other objects in view, which will more readily appear as the nature of the invention is better understood, the same consists in the novel construction, combination and arrangement of parts herein-after more fully described, illustrated and claimed.

A preferred and practical embodiment of the invention is shown in the accompanying drawings, in which:—

Figure 1 is a longitudinal sectional view of one form of the improved device.

Figure 2 is a side elevation, partly in section, the line of section being indicated at 2—2 in Figure 1.

Figure 3 is a detail cross-sectional view taken on the line 3—3 of Figure 1.

Figure 4 is a longitudinal sectional view of another form of the device.

Figure 5 is a cross-sectional view taken on the line 5—5 of Figure 4.

Figure 6 is a graph showing curves giving the vacuum force with the piston maintained at rest at any point along each of such curves at a constant engine speed. Each of said curves is plotted at a different constant speed, the upper curve representing the highest engine speed for which the governor is adjusted and each successive curve showing a lesser constant engine speed, progressively varying from the upper curve and from each other by a small amount, such as 25 R. P. M. all with wide open throttle.

The point P represents the maximum speed for which the governor is adjusted. The curve OP represents the spring resistance, the lesser resistance of the springs below the point P as compared with the vacuum force.

being necessary to compensate for inertia and friction of the moving parts and to eliminate surging.

Similar reference characters designate 5 corresponding parts throughout the several figures of the drawings.

In the embodiment of the invention shown in the several figures of the accompanying drawings, it will be observed that the same 10 essentially includes in its organization a body or casing A provided with attaching means B for connecting the same in the intake duct of an internal combustion engine at a suitable point between the manually controlled throttle valve and the engine. The said body or casing A includes a transverse passage C adapted to register with the intake passage or duct to the motor or engine, and is also provided with a piston 20 chamber designated generally as D, axially arranged at right angles to the passage C and having therein an integral vacuum responsive element designated generally as E and governing valve F.

25 Both forms of the invention shown in the drawings include the above fundamental features and reference will now be made more in detail to the structural features and characteristics of the special embodiments 30 shown in the drawings.

Referring first to Figures 1 and 2, it will be observed that the passageway C is formed with a port which is of lesser diameter than the governing valve F and is bored in axial 35 alignment with the piston chamber D so as to form a guide 1 for the governing valve F. The chamber D having two diameters designated at 2 and 3, thereby forming the interior shoulders 4 and 5. The portion of 40 the chamber D of largest diameter may be fitted with a bushing 6 for the purpose of reducing friction between the piston head and the chamber, as will be readily apparent.

45 The chamber D is adapted to be closed by a cover disc 7 having openings 8 therein for communicating with the atmosphere. As shown, a guard plate 9 may be used, the same being held to the cover by the fastenings 10 which also hold the cover to the body A. The guard plate 9 merely protects the openings 8 and communication between the atmosphere and the ports 8 may be maintained through a plurality of peripheral depressions 9^a formed in the edge of the cover.

55 The end of the body A opposite the cover 7 is provided with an off-set boss 11 having a bore 12 whose axis is in line with the axis of the chamber D, and which is enlarged 60 as indicated at 13 to receive a bushing 14 which guides the stem portion 15 of the vacuum responsive element E as will presently appear.

65 The chamber D communicates with the intake line or passage on the engine side of

the valve F by means of the holes a (Figure 3), and the by-pass formed by the communicating bores 16, 17 and 18 on the throttle side of the governing valve. With the arrangement described it will be apparent that 70 the said chamber D is adapted to communicate with the passage C on both sides of the governing valve, the holes a being positioned down-stream from the governing valve and the by-pass 16, 17 and 18 being positioned 75 up-stream from said valve. In order to control or regulate the drop in pressure within the chamber, the passage 16 is provided with an adjusting screw 16^a which controls the flow of mixture through the by-pass 16, 17 80 and 18. The intensity of the vacuum pulling on the piston from the engine side of the governing valve may therefore be regulated through the by-pass by manipulating and setting the screw 16^a. It will be observed 85 that merely for the purpose of insuring continuity of communication through the by-pass, the portion 18 thereof is plugged at 18^a. This regulation is desirable to compensate for slight variations in the springs and 90 varient leaks past the piston 20.

Referring now more in detail to the said piston device, it will be observed that the same includes hollow body 19 having at one end thereof a piston head 20 adapted to 95 slide in the bushing 6. As previously explained the guide stem 15 has a sliding engagement with the bushing 14 and therefore the plunger device is supported and guided by the stem 15 and piston part or head 20. 100 The stem 15 is therefore important since it prevents canting or cocking of the piston in its movement and thereby reduces frictional resistance from that cause. To avoid air pocketing in the bore 12, the stem 15 is provided with the longitudinal bore 15^a and the transverse bore 15^b opening up-stream from 105 the governing valve.

The piston-element is normally held in the position shown in Figure 1 by the spring 21. 110 This spring is confined between the shoulder 4 and the underside of the piston head 20, and the convolutions thereof adjacent the shoulder 4 are spaced closer together than the convolutions at the opposite end to provide a spring of variable pitch.

The characteristics of the ordinary compression spring are substantially straight lines and hence are not suitable for the present device. The pitch of the coil of the 115 spring 21 varies in such fashion that as it is loaded, more and more of its coils become solidly compressed, thus causing a diminution of the total number of active coils or convolutions in the spring and gradually 120 making it stiffer, so that a smooth resistance curve of the required characteristics is obtained.

125 The cover 7 is provided with an internally threaded boss 7^a which receives the threaded 130

end of a stud 22 whose opposite end is provided with a head 23. This head is adapted to be engaged by a spring 24 carried by the shank of the stud 22 and the end 25 of said 5 spring is adapted to be engaged by the washer 26 carried by the piston head 20 through the medium of the spring locking ring 27. It will be observed that the washer 26 has a central opening to receive the shank 10 of the stud 22 so that no friction will occur between the washer and the stud.

The auxiliary spring 24 is provided for the adjustment of the no-load speed. The characteristics of the spring 24 are such that 15 when combined with the variable pitch spring 21, they jointly produce a curve as shown by the line OP in Fig. 6.

The pull on the piston developed at point O of Fig. 6 is not very large. Since more 20 positive operation is obtained where larger forces are utilized it is not desirable to change the value of the latter forces. The vacuum adjustment provided is accordingly 25 designed so as to accomplish this result, for when the passage C is wide open, the difference in pressure between the points where the by-pass vapor enters and where it leaves the by-pass, is negligible. However, as the 30 governing valve F moves across the port C', to close the passage, this difference in pressure increases more and more rapidly, and hence the flow of vapor is similarly affected.

From the foregoing description it will be 35 apparent that when the governing valve F is in full open position, that is, under the full influence of the spring 21, the open area of the passage C is sufficient to admit a quantity of fuel which will enable the engine to deliver full power. On the other hand, 40 when the valve F has moved all the way in, until the piston 20 rests on the shoulder 5, the area of the passage C will only be sufficient to permit the engine to idle at a speed somewhat lower than the governed speed 45 due to the closing of the valve F.

If the speed of the engine is maintained 50 constant by the application of proper loads while the piston is permitted to assume various positions throughout its movement, and the force upon this piston is measured, it 55 will be found that the force is not proportional to the movement of the piston, but that as the piston moves to close the passage, the force acting upon it first increases slowly and then very rapidly. If a series of such 60 constant speed tests be performed by varying the constant speed by a small amount, such as 25 revolutions per minute, and the results represented graphically, a number of 65 curves is obtained substantially as shown in Figure 6. It is obvious, from these curves, that if the change in speed between full load and no load is to be small, the characteristics of the controlling spring must be such 70 as to develop a resistance equal to the pull

on the piston at point O of curve #1, where the passage C is wide open, and a resistance equal to the pull on the piston at point P of curve #4, when the passage C is closed and the engine is carrying no load at the required 75 speed. Moreover, if the operation is to be stable throughout the spring resistance curve must be such that at all points up to the engine speed for which the governor is adjusted, the spring resistance will be slightly 80 in excess of the pull on the piston, or in other words said valve will be biased toward the open position at all engine speeds below the maximum for which the governor is adjusted.

Referring to the embodiment of the invention shown in Figures 4 and 5 it will be apparent that all of the essential features and characteristics of the device shown in Figures 1 to 3 are adhered to, the main difference being in the utilization of a different arrangement of springs to resist the effect of vacuum effort on the piston 20^a.

As will be observed from Figure 4, the spring 21^a surrounding the body 19^a of the piston-plunger E, has coils that are uniformly spaced. It will also be seen that the stud 22^a carried by the cover 7^a has thereon two springs, viz 24^a and 24^b; 24^a being a relatively weak spring and the spring 24^b being 90 a stronger spring and adapted to collapse in the order named when the spring 24^b is engaged by the washer 26^a carried by the piston head 20^a. Thus, in this arrangement, three springs are utilized instead of the two 95 springs as shown in Fig. 1. The result however, is the same.

In this embodiment of the invention the cover 7^a is provided with atmosphere ports 8^a so that atmospheric pressure may act on 105 the piston head 20^a, and also chamber D communicates with the intake side of the passage C through the by-pass 16', 17' and 18', the passage 16' of the by-pass being controlled by the screw 16^b. On the other hand the 110 down-stream side of the passage C communicates with the chamber D through the passage a'.

As the operation of this type of device is the same as the operation of the device shown 115 in Figs. 1 and 2; the only difference being that the design of Figs. 4 and 5 is adapted for a different type motor; a further detail description of this device will not be given.

Without further description it is thought 120 that the features and advantages of the invention will be readily apparent to those skilled in the art, and it will of course be understood that changes in the form, proportion and minor details of construction 125 may be resorted to, without departing from the spirit of the invention and scope of the appended claims.

We claim:-

1. An automatic governor for internal 130

combustion engines comprising a vacuum responsive member and a governing valve member directly connected for movement in unison, and spring resistance means associated with one of said members to provide for unequal increments in spring pressure, an initially large reduction of the area of the passage-way and then a progressively diminishing reduction of the area of the passage-way.

2. An automatic governor for internal combustion engines comprising a vacuum responsive member and a governing valve directly connected for movement in unison, and spring resistance means associated with the vacuum responsive member to provide for unequal increments in spring pressure, and initially large reduction of the area of the fuel passage-way and then a progressively diminishing reduction of the area of said passage-way.

3. An automatic governor for internal combustion engines comprising a vacuum responsive member and a governing valve member directly connected for movement in unison, and spring resistance means associated with one of said members and adapted to permit of an initially large reduction of the area of the passage-way and then a diminishing reduction of the area of the passage-way, said spring resistance means including a plurality of springs of differential resistance, and certain of said springs being mounted on an adjustable support.

4. An automatic governor for internal combustion engines comprising a casing adapted to be interposed in the mixture intake duct to the engine and having a chamber and a fuel passage, a combined vacuum responsive member and governing valve slidably mounted in the casing and having a piston part disposed in said chamber and a valve part adapted to be projected across said passage-way, and spring resistance means associated with the vacuum responsive member and adapted to permit of an initially large reduction of the area of the passage-way and then a progressively diminishing reduction of the area of said passage-way.

5. An automatic governor for internal combustion engines comprising a casing having a chamber and a passage-way adapted to register with the intake line, and a combined vacuum responsive member and governing valve arranged in the casing and including a piston part operating in the chamber and a valve part operating across the passage-way, spring resistance means associated with the vacuum responsive member and adapted to permit said vacuum responsive element and governing valve to move to effect an initially large reduction of the area of the passage-way and then a pro-

gressively diminishing reduction of the area of the passage-way, and ports in said casing for establishing communication between said chamber and opposite sides of the valve.

6. An automatic governor for internal combustion engines comprising a casing having a chamber and a passage-way adapted to register with the intake line, and a combined vacuum responsive member and governing valve arranged in the casing and including a piston part operating in the chamber and a valve part operating across the passage-way, spring resistance means associated with the vacuum responsive member and adapted to permit said vacuum responsive element and governing valve to move to effect an initially large reduction of the area of the passage-way and then a progressively diminishing reduction of the area of the passage-way, ports in said casing for establishing communication between said chamber and opposite sides of the valve, and means associated with one of said ports for throttling the same.

7. An automatic governor for internal combustion engines comprising a casing having a chamber and a fuel passage-way adapted to register with the intake pipe line of the engine, a combined vacuum responsive element and governing valve arranged in said chamber and including a piston part and a valve part adapted to be projected across said passage-way, spring resistance means arranged in said chamber and cooperating with the vacuum responsive element, means for permitting atmospheric pressure to exert its force on one side of the piston part of the vacuum responsive element, means for permitting the vacuum to exert its influence at the other side of the piston, and means for regulating the intensity of the vacuum operating on said piston.

8. An automatic governor for internal combustion engines comprising a casing having a vacuum chamber, a fuel passage-way adapted to register with the intake pipe line of the engine, a combined vacuum responsive element and governing valve arranged within the casing and including a piston part operating within the chamber and a valve part adapted to be projected across the passage-way, spring resistance means operating in conjunction with the piston part of the vacuum responsive element, a ported cover secured to the casing and adapted to permit atmospheric pressure to reach one end of the piston, ports in the casing for establishing communication between the engine side of the passage-way and the vacuum chamber, a by-pass establishing communication between the manually controlled throttle side of the passage-way and said vacuum chamber, and means for regulating the flow of vapor through the by-pass.

9. An automatic governor for internal

- combustion engines comprising a casing having a vacuum chamber and a fuel passage-way, a combined vacuum responsive element and governing valve arranged in the chamber and governing valve arranged in the chamber and including a piston part operating in the vacuum chamber and a valve part adapted to operate across the passage-way, spring resistance means associated with the piston part of the vacuum responsive element, and means for guiding the valve part in its movement independently of its contact in the passage-way, whereby the combined vacuum responsive element and governing valve is supported in its movement by said means and the piston part.
10. An automatic governor for internal combustion engines comprising a casing having a vacuum chamber and a fuel passage, a vacuum responsive member and a governing member arranged in said casing and including a hollow body having a piston head at one end adapted to operate in the chamber and having a valve part at its opposite end adapted to operate across the passage-way, a cover for the chamber having ports for permitting atmospheric pressure to reach one end of the piston, ports between opposite sides of the valve part and the chamber, and spring resistance means adapted to permit a move-
- ment of the vacuum responsive element and valve device whereby an initially large reduction is effected in the area of the passage-way and then a progressively diminishing reduction of the area of said passage-way, said spring resistance means including a plurality of springs of differential resistance respectively mounted within and outside of said hollow body, a support carried by the cover for carrying a part of the spring means within the hollow body, and means carried by the piston part of the vacuum responsive element for engaging with a spring on the support.
11. An automatic governor for internal combustion engines comprising a vacuum responsive member and a governing valve member directly connected for movement in unison and spring resistance means associated with one of said members for unequal increments in spring pressure, an initially large reduction of the area of the passage-way and then a progressively diminishing reduction of the area of the passageway, said valve being biased toward the open position at all engine speeds below the maximum for which the governor is adjusted.
